US00D429274S

United States Patent [19]

Kobayashi

[11] Patent Number: Des. 429,274

[45] Date of Patent:  Aug. 8, 2000

[54] TYPE FONT

[75] Inventor: Akira Kobayashi, Tokyo, Japan

[73] Assignee: Adobe Systems Incorporated, San Jose, Calif.

[] Term: 14 Years

[21] Appl. No.: 29/111,707

[22] Filed: Oct. 1, 1999

[51] LOC (7) Cl. 18-03

[52] U.S. Cl. D18/24

[58] Field of Search D18/24-33
